WRISTBAND

Gordon D. Drewry, West Henrietta, N. Y.

Application April 19, 1945, Serial No. 589,233

2 Claims. (Cl. 224—4)

1

This invention relates to a band or strap such as is useful in holding a wrist watch, locket, or other article on the wrist or arm of the wearer, although it may be applied also to other suitable portions of the anatomy such as the ankle or leg. An object of the invention is the provision of a generally improved and more satisfactory article of this character.

Another object is the provision of a band consisting of a minimum number of parts, so designed and constructed that it may be instantly applied or removed without the necessity for fastening or loosening buckles, clasps, or other fastening devices.

Still another object is the provision of such a band, so designed and constructed as to be comfortable to the wearer.

A further object is the provision of a simple, inexpensive, and efficient device, of neat and attractive appearance, more easily and quickly applied and removed than prior devices of this general character.

These and other desirable objects are accomplished by the construction disclosed as an illustrative embodiment of the invention in the following description and in the accompanying drawings forming a part hereof, in which:

Fig. 1 is an edge view of a preferred form of wrist band according to the present invention, showing it in closed position:

Fig. 2 is a similar view in partially opened position.

Fig. 3 is a cross section taken substantially on the line 3-3 of Fig. 1; and Fig. 4 is a similar cross section illustrating an alternative shape of hand.

The same reference numerals throughout the views indicate the same parts.

The wrist band of the present invention is to be distinguished at the outset from those bands or bracelets which, on the one hand, require catches, clasps, or buckles to keep them closed, and from those which, on the other hand, are kept closed by special springs or resilient mem- 40

Kept closed by special springs or resilient members other than or supplementary to the band 45 members themselves. It is also to be distinguished from those bands which must be kept forcibly distended to an appreciable extent while being put on or removed from the wrist, and from those bands which extend only part way 50 around the wrist, rather than encircling the entire circumference of the wrist. As distinguished from them, the improved band of the present invention completely encircles the wrist, requires but slight force to open it (without requiring 55

manipulation of buckles, catches, etc.) and when it has been opened it remains open, readily placeable on or removable from the wrist, until a slight force is applied to close it.

5 The band comprises, in its preferred form, a pair of cooperating curved members 11 and 13, pivoted either directly to each other or preferably to the ends of an intermediate object such as a wrist watch or locket 15, by means of simple pivots 17 and 19, requiring no springs in connection with these pivots to tend to turn the members 11 and 13 in one direction or the other.

Both of the strap members 11 and 13 are made of resilient or springy material, such as resilient metal or resilient molded plastic material, and their normal undeformed shape is the shape shown in Figs. 1 and 2, somewhat elliptical so as to fit the normal wrist of generally elliptical cross section, each of the straps 11 and 13 extend through more than half, and preferably about three-quarters, of the circumference of the ellipse, as readily seen in the drawings. Both straps 11 and 13 are made sufficiently wide (as shown in Fig. 3) so that one overlies the other firmly, with no danger of slipping laterally off of the other in spite of any moderate amount of looseness that may be present in the two pivots 17 and 19, which pivots are, of course, substantially parallel to each other, and which hold the two straps 11 and 13 so that they swing in the same plane.

If, however, it is desired to make the straps somewhat narrower than the proportions shown in Fig. 3, this may be done by making the inner strap 11 with an outer surface which is convex in cross section, as indicated at 11a in Fig. 4, and by making the outer strap 13 with an inner surface which is concave in cross section, as indicated at 13a in Fig. 4, so that the curvature of the cooperating surfaces of the two straps will tend to hold them against lateral displacement relative to each other. The two straps are of substantially the same configuration so that one hugs closely against the other as indicated in Fig. 1.

Fig. 1. 45 The operation of the device is as follows: The two strips 11 and 13 are opened up and turned back away from each other, and likewise turned back relative to any object to which they may be pivoted, such as the wrist watch or locket 15. 50 The band 11 is then slipped over the wrist, which is done readily without any particular distension required, since the open space between the pivot 17 and the extreme free end 21 of this band is amply sufficient to allow easy passage of the wrist, 55 with little or no distension of the band. Then

with the band 11 on the wrist, the wrist watch or other article 15 is folded down onto the wrist and the other band 13 is closed around the outside of the first band 11. During the closing operation, the extreme free end 23 of the band 13 will slide over the outer surface of the band 11, and the band 11 will act somewhat as a cam, distending or opening up the band 13 during the closing operation, until the end 23 of the band 13 passes over the "high point" of the cam formed by the strap 11, after which the further closing motion of the strap 13 permits this strap to contract once more to its normal shape, until finally the strap 13 lies tight against the outside of the strap 11, as indicated at Fig. 1.

Referring especially to Fig. 2, which shows the straps 11 and 13 at an intermediate position in the closing or opening operation, it is seen that if pressure is applied to the outer strap 13 in the general direction of the arrow 25, such pressure will cause the free end 23 to ride leftwardly along the lower outer surface of the strap 11, and during such motion the strap 11 will cam the end 23 outwardly, farther away from the pivot 19, until the "high point" of the member 11 with respect to the pivot 19 is reached. The dotted line 27 in Fig. 2 represents an arc of a circle struck from the pivot 19 as a center, and indicates that the "high point" is somewhere in the vicinity of the arrow 29, but it will not be at exactly this point because as the strap 13 closes, it will coact with the free end 21 of the strap 11 to swing this strap 11 somewhat in a clockwise direction about its pivot 17 with respect to the wrist watch 15, so that by the time the end 23 of the strap 13 reaches the arrow 29 (which is the apparent high point when the parts are placed as in Fig. 2) the pivot 19 and the strap 11 will have moved relatively to each other and the high point will likewise have moved to some extent, but it will still be in the same approximate location as indicated.

When the strap 13 has closed completely on the strap 11, to the position shown in Fig. 1, the resilience of the parts keeps them closed, without the necessity for any clasps, or any springs other than the bands or straps 11 and 13 themselves. This is so because in any opening motion of the strap 13, the free end 23 thereof must be cammed farther away from the pivot 19 (against the spring force of the strap 13 itself) until the high point of the strap 11 has been passed, and thus until such high point has been passed the resilience of the strap automatically tends to hold itself closed. But by the exertion of slight force, the strap 13 may instantly be opened up until the end 23 thereof has passed the high point of

the member 11, and then the two straps may be completely opened to remove the unit from the wrist. The strap 13 may be placed inside and the strap 11 outside, if desired, and the same action will result, both straps 11 and 13 being similarly made of the same resilient or springy material. This interchangeability of the two straps 11 and 13 is true, of course, of the flat cross sectional form shown in Fig. 3, but if narrower straps of concavo-convex cross section are used, as indicated in Fig. 4, then the design is such that the strap 11a should normally always be the inside one, and the strap 13a should be outside.

It is seen from the foregoing disclosure that a construction is provided which admirably fulfills the above-mentioned objects of the invention. It is to be understood that the foregoing disclosure is given by way of illustrative example only, rather than by way of limitation, and that without departing from the invention, the construction may be varied within the scope of the appended claims.

What is claimed is:

1. A wrist band including an intermediate object such as a watch and two resilient members pivotally connected to opposite ends of said object and adapted to swing relative to each other in substantially the same plane, said members being curved to form, with said object, a closed loop to encircle a wrist with the free ends of said members overlapping, each member extending through more than half of the circumference of said loop whereby the resiliency of said members will maintain said loop closed without the use of other means and will permit said free ends to be readily separated to open said loop for passage of the wrist.

2. A structure as defined in claim 1 in which each of said two resilient members is in the form of a metal strip considerably wider than its thickness, and each of them extends about three-quarters of the way around the circumference of said loop.
